UNITED STATES PATENT OFFICE

ORVILLE NELL, OF BRIDGEPORT, ILLINOIS
 SWITCH OPERATING AND LOCKING MEANS

Application filed October 4, 1929. Serial No. 397,320.

The invention aims to generally improve upon the construction shown by my U. S. Patent No. 1,087,046 of February 10, 1914, and with this end in view, the invention resides in the novel subject matter hereinafter described and claimed, description being accomplished by reference to the accompanying drawing.

Fig. 1 is a top plan view of a switch and the improved operating and locking means associated therewith.

Fig. 2 is a vertical sectional view on line 2—2 of Fig. 1 showing the switch locked in closed position.

Fig. 3 is a sectional view on line 3—3 of Fig. 1 also showing the switch locked in closed position.

Fig. 4 is a duplicate of Fig. 3 with the exception that it illustrates the switch in open position, the locking means thereof being released.

Fig. 5 is a perspective view of the bridle bar.

Fig. 6 is a perspective view of the lock-releasing bar.

In the drawings above briefly described, the numerals 7 and 8 denote conventional switch tongues, and 9 has reference to a bridle bar connected with said tongues at the points 10. This bridle bar is provided at one end with a short longitudinal slot 11 and near its other end is formed with an inwardly facing shoulder 12 which may well be provided by the inner end of an insulating connection 13 between two sections of the bar 9, this construction being used in some instances to prevent signalling or other current from passing from the tongue 7 to the switch stand 14 or to the tongue 8 and adjacent rail.

Parallel with the bridle bar 9, is a locking bar 15 for the tongue 8, said bar being provided in its upper edge with a notch 16 to receive said tongue 8 and the adjacent rail 17. The bar 15 is pivotally mounted at 18 upon an appropriate supporting bar 19 which extends between and is secured to two of the cross ties 20. The other end of the bar 15 is provided with a lateral projection 21 extending to a point beneath the bridle bar 9, this projection being preferably in the form of a

roller. Beyond the roller or the like 21, a suitable spring device 22 may be associated with the locking bar 15 and an overlying stationary bar 23 to assist in raising said locking bar but due to the construction of an operating cam which is provided for said bar 15, it is not essential that the spring device 22 be employed.

A lock-releasing bar 24 lies slidably against the lower side of the bridle bar 9 and is provided at one end with a rigidly attached yoke 25 which slidably surrounds said bridle bar at the inner end of the connection 13. The other end of the bar 24 underlies the slot 11 and an actuator 26 which may be moved in one direction or the other by the switch stand 14, is provided with a portion 27 passing through the slot 11 and directly connected with the bar 24.

Near its inner end, the bar 24 is provided with a rigidly attached downwardly projecting plate 28 having a cam slot 29 formed therein, said cam slot having a horizontal end 30 and an inclined end 31. The slot end 31 normally receives the roller or other projection 21 as seen in Fig. 3 and consequently holds the locking bar 15 in its raised locking position. When the actuator 26 is inwardly moved by the switch stand, its portion 27 slides in the slot 11 and said actuator thus inwardly slides the latch releasing bar 24 with respect to the bridle bar 9, the result being that the inclined slot end 31 depresses the locking bar 24 as seen in Fig. 4, thereby releasing the tongue 8. By the time this has taken place, the yoke 25 has come in contact with the shoulder 12 as seen in Fig. 4 so that further inward sliding of the bar 24 under the influence of the actuator 26, will slide the bridle bar 9 to move the switch tongues 7—8 to open position. Reversal of the movement of the actuator 26 first restores the tongues 7—8 to closed position, due to the horizontal slot end 30 and then causes the inclined slot end 31 to thrust upwardly upon the projection 21, thereby forcing the locking bar 15 to its raised locking position and holding it in said position.

The yoke 25 forms a more effective sliding connection between the inner end of the bar

24 and the bridle bar 9 than the connection disclosed in my old patent, and the plate 28 with its cam slot 29 constitutes an important improvement in that it not only functions to release the locking bar 15, but also acts to positively restore said locking bar to its locking position, and further serves to hold it in locking position.

10 The general construction disclosed is preferably followed on account of the existing advantages. However, within the scope of the invention as claimed, numerous variations and improvements may be made and it will be understood that I am not restricted to materials, size, proportion, etc.

15 I claim:—

1. In a switch operating and locking means, a bridle bar for connection with the usual tongues, a vertically movable tongue-locking bar parallel with said bridle bar and having a lateral projection under the latter, a lock-releasing bar slidably mounted under, extending longitudinally of and having a lost motion connection with said bridle bar, and 20 a vertical plate secured to and projecting downwardly from said lock-releasing bar, said plate having a slot receiving said lateral projection, said slot being provided with a horizontal end and an inclined end, said 25 inclined slot end normally engaging said lateral projection to hold said locking bar in raised tongue-holding position and standing in readiness to depress said locking bar to released position upon sliding of said lock- 30 releasing bar with respect to the bridle bar, said horizontal slot end receiving said lateral projection upon unitary movement of locking bar and bridle bar after release of 35 said locking bar.

2. In a switch operating and locking means, a tongue-connecting bridle bar having a slot at one end and an inwardly facing shoulder near its other end, a tongue lock, a 40 releasing bar for said lock lying slidably against the lower side of said bridle bar and operatively connected with said lock, a yoke rigid with one end of said lock-releasing bar and slidably surrounding said bridle bar, said 45 yoke being adapted to thrust against said shoulder to move the switch tongues to open position, and an actuator for said bars, said 50 actuator having a portion passing through said slot and connected with said lock-releasing bar.

55 In testimony whereof I have hereunto affixed my signature.

ORVILLE NELL.
